UNITED STATES PATENT OFFICE.

JOHN B. CHEIVER AND JOHN BURCHAM, OF SAN DIEGO, CALIFORNIA.

DESIGN FOR A SCRAPER-HOLDER.

52,765.

Specification for Design.

Patented Dec. 17, 1918.

Application filed May 7, 1917. Serial No. 167,140. Term of patent 3½ years.

To all whom it may concern:

Be it known that we, JOHN B. CHEIVER and JOHN BURCHAM, citizens of the United States, residing at San Diego, in the county of San Diego and State of California, have invented a new, original, and ornamental Design for a Scraper-Holder, of which the following is a specification, reference being had to the accompanying drawing, forming part thereof.

The figure is a perspective view of a scraper holder, showing our new design.

We claim:—

The ornamental design for a scraper holder, as shown.

JOHN B. CHEIVER.
JOHN BURCHAM.

Witnesses:

GEO. W. BOWLER,
MELBA G. MILZ.
